UNITED STATES PATENT OFFICE.

JOHN MILLAR, OF BETHNAL HOUSE, CAMBRIDGE ROAD, COUNTY OF MIDDLESEX, ENGLAND.

TIME-CHECK.

SPECIFICATION forming part of Letters Patent No. 354,921, dated December 28, 1886.

Application filed February 10, 1886. Serial No. 191,454. (No model.)

To all whom it may concern:

Be it known that I, JOHN MILLAR, a subject of the Queen of Great Britain, residing at Bethnal House, Cambridge Road, in the county of Middlesex, England, physician, have invented 5 certain new and useful Improvements in Tell-Tale Time-Keepers, of which the following is a specification.

My invention relates to improvements in a 10 tell tale time-keeper of the class in which a clock of suitable construction is provided with a paper disk suitably marked replacing the hands and revolving, say, in twelve hours.

This clock is locked up in a box, and there 15 is a hole in the door or cover of the box through which a pencil can be inserted and made to mark on the paper disk. The clock so locked up is fixed at the station to be visited by the watchman.

20 To prevent or detect tampering with the apparatus by opening the box with a false key, and then marking the disk in a manner to deceive, there is provided a sheet of transfer-paper beneath the disk, but separated from it 25 by an intermediate surface of card-board or other material with an aperture in it. The aperture coincides with the hole in the door or cover of the case. The transfer-paper and the separating material are so fixed in the clock as 30 not to revolve with the disk. When the disk is marked in a legitimate way in addition to the mark on the face, a corresponding mark is produced on the back by the transfer-paper.

In accordance with my improvements in tell-tale time-keepers of the above outlined type, 35 the position of the clock in the box can be altered to render the necessary changes of the paper disk less frequent, and to defeat any attempt to remove and replace the paper disk I 40 employ a circular nut of large diameter to confine the disk upon the hour-axis of the clock. I form a small perforation in this nut, and when the paper disk is in place I mark it with a pin inserted through this perforation. Similarly 45 before changing the disk I again insert the point of a pin into the perforation, which, if the disk has been tampered with, marks it a second time, but if not passes through the original perforation.

50 In order that my said invention may be fully understood and readily carried into effect, I

will proceed to describe the drawings hereunto annexed.

In the drawings, Figure 1 is a front elevation of the tell-tale clock, the door of the case being 55 open. Fig. 2 shows the record-disk separately. Fig. 3 shows the surface of card-board or other material behind the paper disk. Fig. 4 shows the transfer-disk. Fig. 5 shows a metallic table or surface supporting the preceding parts and 60 serving to inclose the clock-train. Fig. 6 shows a portion of the hour-axis of the clock. Fig. 7 is a view, partly in vertical section and partly in elevation, of the time-keeper.

a is the case. It has a door, and it is provided with a lock. At *a'* is the hole in the door, by which, when the case is closed, the pencil is inserted for the purpose of marking the record-disk.

b is the record-disk. It is of paper. The 70 hole in the center of the record-disk, through which the hour-axis of the clock-train passes, is made to receive the axis loosely, so as to increase the difficulty of tampering with the nut and record-disk and readjusting them after 75 movement to their previous position.

c is the hour-axis of the clock. It has a collar, *c'*, upon it, and is screwed to receive a large flat nut, *d*. The record-disk *b*, when in place, is clipped between the collar *c'* and the nut *d*. 80

d is the perforation in the nut *d* for the insertion of a pin-point to mark the record-disk, so that when set it may not be removed and re-placed without detection.

e is the surface interposed between the record-disk and the transfer-disk.

f is the transfer-disk. It only marks the back of the record-disk when the pencil is legitimately applied to the face—that is to say, through the hole *a'*—and then the point of the 90 pencil meets the gap *e* in the surface *e*. The interior vertical dimension of the case exceeds the height of the clock in order that the clock may be vertically adjusted and supported at different levels.

g, *g'* are shallow blocks, which may be placed in the case beneath the clock to raise it when the record-disk has been already marked, so that the record-disk may serve for more than one record, and that marks afterward made 100 may not interfere or be confused with previous marks. The blocks *g*, *g'*, when not in use, rest

above the clock, as shown. Colored pencils may also be employed to distinguish the records, so that more than one record may be made on the same part of the record-disk without confusion.

By employing pencils of three colors to mark the outer ring of the record-disk and raising the clock by the successive use of first one and then both of the blocks g' and g'' , and marking the inner rings with pencils of two colors, it will be necessary to change the record-disks only once a week.

Having now particularly described and ascertained the nature of my said invention, and in what manner the same is to be performed, I declare that what I claim is—

The combination of the case a , having the

pencil-hole a' , the clock-train within the case, the hour-axis of the clock-train, having the collar c' , the record-disk b , loosely embracing the hour-axis, the nut d , screwed on the axis and clipping the record-disk against the collar thereof, and having the perforation d' to admit of the insertion of a pin for marking the record-disk, the transfer-disk f , and the surface e between the transfer-paper and record-disk, and having the gap e' , substantially as and for the purpose set forth.

JOHN MILLAR.
